HYDRAULIC PUMPING JACK

Lloyd Spencer, Alhambra, Calif., assignor to
 Lane-Wells Company, Los Angeles, Calif., a
 corporation of Delaware

Application September 21, 1936, Serial No. 101,729

20 Claims. (Cl. 60—52).

My invention relates to hydraulic pumping jacks, and among the objects of my invention are:

First, to provide a hydraulic pumping jack which is adapted to pump relatively shallow wells capable of being pumped efficiently without or with only partial counterbalancing.

Second, to provide a hydraulic pumping jack which is particularly designed for "stripper wells"; that is, wells in the last stages of production.

Third, to provide a hydraulic pumping jack wherein the preponderance of the pumping cycle may be occupied by the working stroke and which incorporates means whereby the duration of the return stroke, and consequently the duration of the entire pumping cycle, may be readily and quickly varied.

Fourth, to provide a hydraulic pumping jack which minimizes the plunge velocity of the well pump during its working stroke and tends to offset any lost efficiency due to the uncounterbalanced weight of the sucker rods.

Fifth, to provide a pumping jack which imparts during both the working and return strokes a substantially constant velocity to the sucker rods.

Sixth, to provide a hydraulic pumping jack which incorporates a special control valve so arranged as to eliminate any mechanical connection between the valve and moving parts of the pumping jack.

Seventh, to provide a hydraulic pumping jack wherein only the jack cylinder and piston need be located over the well mouth; the remaining elements thereof comprising a fluid pressure source, control valve, and reservoir arranged in a compact unit located arbitrarily with respect to the jack cylinder and connected therewith by a single pipe line, thereby providing a hydraulic pumping jack which is particularly easy to install and service even on wells having no surface equipment.

Eighth, to provide a novel control valve for a hydraulic pumping jack piston and cylinder, which valve disconnects the cylinder from a pressure source when the pressure in the cylinder exceeds a predetermined value and reconnects the cylinder with the pressure source when the pressure in said cylinder falls below a predetermined value.

Ninth, to provide a hydraulic pumping jack having cylinder and piston means which incorporate a cushioning device operable at the lower end of its pumping stroke, and a piston retarding means operable at the upper end of the pumping stroke

to create pressure conditions in said cylinder below and above a predetermined range in order to affect a control valve associated therewith.

Tenth, to provide a hydraulic pumping jack which, should the pressure within the jack cylinder exceed a predetermined value, automatically reverses movement regardless of the amount of stroke completed; thus providing a safety feature which minimizes the possibility of pulling the sucker rods in two or exerting an excessive strain thereon.

Eleventh, to provide a hydraulic pumping jack which tends automatically to work the well pump free of deleterious matter such as sand or the like without the attendance of an operator; said hydraulic jack limiting its working stroke upon binding of the well pump until such deleterious matter is worked free and then resuming its full working stroke.

Twelfth, to provide a hydraulic pumping jack which incorporates a readily accessible, manually operable means for increasing the pressure required to effect reversal in movement on completion of the working stroke, so that when starting the pumping jack after idle periods, or for other reasons, the pumping jack may be caused to exert temporarily an additional pull on the sucker rods; said manually adjustable means in no way affecting the normal adjustment of the pumping jack.

With the above and other objects in view as may appear hereinafter, reference is made to the accompanying drawings, in which:

Fig. 1 is a partially elevational, partially sectional view illustrating one form of my pumping jack.

Fig. 2 is an enlarged, fragmentary, sectional view taken through 2—2 of Fig. 1 showing particularly the dashpot arrangement for cushioning downward movement of the jack piston.

Fig. 3 is a transverse sectional view through 3—3 of Fig. 2.

Fig. 4 is an enlarged sectional view of the control valve taken substantially through 4—4 of Fig. 1 showing the parts of the valve in the position assumed when the pumping jack is at rest at the bottom of its stroke or during its working stroke.

Fig. 5 is a similar sectional view showing the parts of the valve in the position assumed immediately upon reversal prior to the starting of the down or return stroke.

Fig. 6 is a sectional view through 6—6 of Fig. 1 showing particularly the choke valve for controlling the rate of the return stroke.

Fig. 7 is a sectional view through the control

valve at right angles to Figs. 4 and 5 and taken through 7—7 of Fig. 1.

Fig. 8 is a sectional view through 8—8 of Fig. 4.

5 Fig. 9 is a fragmentary sectional view similar to Figs. 4 and 5 illustrating a modified form of pilot valve which incorporates an auxiliary control.

10 Fig. 10 is an enlarged, fragmentary, sectional view of a modified form of pumping jack and cylinder with the control valve incorporated therein, and including further a hydraulic valve operating device operable independently of the pressure within the jack cylinder.

15 Fig. 11 is a fragmentary, longitudinal, sectional view through 11—11 of Fig. 10 showing particularly the control valve.

Fig. 12 is a transverse sectional view through 12—12 of Fig. 10.

20 Fig. 13 illustrates a further modified form of pumping jack cylinder with parts thereof shown in section.

25 Fig. 14 is a fragmentary elevational view taken at right angles to Fig. 13 and showing the control valve with portions thereof in section.

Fig. 15 is a transverse sectional view through 15—15 of Fig. 13.

Fig. 16 is a graph illustrating the cycle obtainable with my hydraulic pumping jack.

30 In the construction shown in Fig. 1, a reciprocator, indicated generally by 1, is mounted over the production string 2 of a well and is connected by a single pipe 3 to a control valve 4 which, in turn, is connected to a pump 5 and to a reservoir tank 6.

35 The production string is provided with a conventional T 7 having a lateral flow line 8 extending therefrom. A conventional polish rod 9 extends upwardly through the T and through the reciprocator 1.

40 The upper end of the T receives a suitable union 11 having a special threaded stem 12 adapted to screw into the lower end of a cylinder base 13. At the upper end of the stem 12 there is provided a packing gland follower 14 which is adapted to bear against a packing gland 15 formed within the cylinder base 13. A locknut 16 secures the stem 12 in any adjusted position. Bleeder ports 17 are provided in the follower 14 and base 13 so that any leakage past the gland may be visible.

45 Above the packing gland 15, the cylinder base 13 is provided with a sleeve bearing 18, and above said bearing the cylinder base is enlarged to form a dashpot cavity 19. Above the dashpot cavity, the cylinder base is further enlarged to receive the lower end of a cylinder 20. Between the cylinder 20 and dashpot cavity 19, the cylinder base is provided with a lateral port 21.

50 The cylinder 20 is provided with a piston 22 having a bore therethrough for the polish rod 9. The upper end of the piston 22 is threaded to receive a polish rod sleeve 23.

55 A cylinder head 24 is secured to the upper end of the cylinder 20 and is provided with a sleeve bearing 25 and a packing gland 26 through which extends the polish rod sleeve 23 as well as the polish rod 9. At the protruding upper end of the polish rod sleeve there is provided a packing gland 27, and above the packing gland 27 the polish rod is equipped with a clamp 28. The packing gland 26 need serve only to keep the protruding end of the sleeve free of dirt and thereby protect the bearing 25, for the cylinder head 24 is provided with breather ports 29

which may or may not be protected by filters depending on the location and conditions under which the pumping jack is installed.

60 A dashpot plunger 31 is secured to the piston 22 and depends therefrom; said plunger comprises a plunger body 32 having a bore 33 therethrough which is substantially larger than the polish rod so as to form a passage. Lugs 34 may be provided to center the lower end of the plunger body with respect to the polish rod. The upper portion of the plunger body is counterbored to receive an annular or cylinder valve 35 having a valve face 36 at its upper end. The plunger body is further counterbored and internally threaded, and is provided with a valve body 37 having an annular channel 38 in its lower end flanked by valve seats engageable by the valve face 36 of the cylinder valve 35. Passages 39 communicate between the channel 38 and the upper end of the dashpot plunger 31. A weak spring 40 tends to hold the cylinder valve 35 against its seat.

65 The purpose of the valve incorporated in the dashpot plunger is to permit a dashpot action during downward movement of the dashpot plunger in the cavity 19 but admit fluid freely to the dashpot during upward movement of the plunger. The plunger is preferably tapered, or the walls of the cavity may be tapered in order that the dashpot effect may be increased as the plunger moves into cavity.

70 A stop cylinder 41 fits the sleeve 23 above the piston 22, and is provided at its lower end with a flange 42 adapted to support a buffer spring 43 which normally extends above the stop and is adapted to engage the cylinder head 24 as the piston reaches the upper end of its stroke; thus tending to increase the pressure of liquid introduced under the piston.

75 Liquid is alternately introduced and withdrawn through the port 21 to effect reciprocation of the piston; discharge of liquid from under the piston being effected by the weight of the sucker rods.

80 Movement of the reciprocator is effected by the control valve 4 which may be positioned at any point with respect to the reciprocator. The control valve 4 is encased in a housing 51. The housing 51 is provided with a main valve bore which receives a cylindrical liner 52. The bore intersects one end of the housing and is here threaded to receive a sleeve 53 which retains the liner 52 in place. Beginning adjacent but beyond its threaded end, the bore intersects first an exhaust port channel 54, an intake port channel 55, a jack cylinder port channel 56, and a choke valve channel 57; the several channels being separated one from the other, and the liner being perforated opposite these channels for communication therewith.

85 The exhaust port channel 54 merges into a large downwardly directed exhaust port 59 which is adapted to communicate with an exhaust line 59 extending to the reservoir tank 6. The intake port channel 55 intersects a laterally extending intake port 60 which is connected through a line 61 to the discharge side of the pump 5; the intake side of which is connected through a line 62 to said reservoir tank 6. The jack cylinder channel 56 is connected to a jack cylinder port 63 connected with the line 3. The intake and jack cylinder ports 60 and 63 are preferably in alignment and extend in opposite directions at right angles to the exhaust port 58.

90 The choke valve channel 57 merges into a downwardly extending passage 64 which turns

horizontally past the side of the exhaust port 58 and forms a choke valve port 65. The choke valve port 65 is connected by a lateral passage 66 with the exhaust port 58. The housing 51 is 5 provided with an internally threaded bore 67 in horizontal alignment with the choke valve port 65.

The choke valve port 65 is preferably conical and is controlled by a correspondingly shaped 10 choke valve head 68 which is connected by a stem 69 to a threaded traveler 70 mounted in the bore 67 and provided with an outer tool receiving end 71. A locking ring follower 72 also fits the threaded bore 67 to secure the traveler in 15 any adjusted position. The bore 67 is closed by a sealing cap 73 which may be removed for adjusting the choke valve; inasmuch as this valve is in the return line and pressure is nominal, leakage is inconsequential during adjustment 20 operations.

A spool valve 74 is slidably mounted in the liner 52; said spool valve comprises axially spaced sealing flanges 75 and 76. Flange 75 separates the jack cylinder channel 56 from either intake channel 55 or choke channel 57, while sealing flange 76 seals or permits flow between the intake channel 55 and exhaust channel 54. The two positions of the spool valve are shown best in Figs. 4 and 5. In Fig. 4, communication is 30 had between the intake port 60 and the jack cylinder port 63; there being no flow through the other ports. In Fig. 5, the flow occurs simultaneously between the intake port 60 and the exhaust port 58, as well as between the jack cylinder port 63 through the choke valve port 65 into exhaust port 58. The reason for such flow will be brought out in more detail hereinafter.

The sleeve 53 is provided with a spring 77 which bears against the spool valve 74 and is backed by a traveler 78 so as to urge the spool into the position shown in Fig. 4. The sleeve 53 is threaded for said traveler, and also receives a locking ring 79 so that the traveler may be secured in any position in order to adjust the tension of the spring 77. A sealing cap 80 covers the outer end of the sleeve 53 except when adjustment is being made. Inasmuch as the interior of the sleeve 53 is exposed only to the nominal pressure in the exhaust line, the leakage 50 during such adjustment is inconsequential.

The end of the spool valve opposite from the spring 77 is provided with a plunger 81 which fits into a socket 82 continuing from the main bore of the housing. The end of the housing 51 beyond the socket 82 is provided with a lateral bore 83 which communicates with the socket 82 through a small passage 84, and also with the choke valve channel 57 through a passage 85; these passages being arranged side by side. The 60 end of the bore 83 towards the jack cylinder port 63 is in communication therewith through a passage 86. A liner 87 fits the bore 83 and is provided with external channels 88 registering with the passages 84 and 85. The liner 87 is provided 65 with a bore 89 therethrough which is in communication with the channels 88 by ports 90. Between the ports 90, the bore is provided with a valve seat 91 facing towards the ports communicating with passage 84. The inner end of the 70 liner 87 receives a plug 92 having a passage 93 communicating between the bore 89 and passage 86, and having a valve seat facing said bore 89.

A valve 94 fits the bore 89 and is provided with a head 95 having on one side a conical valve element 96 engageable with the valve plug 92, and

a beveled valve element on the other side engageable with valve seat 91. The head does not itself seal the bore in which it rides, but permits slight leakage therearound; sealing being dependent upon engagement with either the valve 5 plug 92 or seat 91.

A stem 97 extends from the valve head 95 through the bore 89, and is guided by a traveler 98. Between the traveler 98 and valve head is mounted a stiff spring 99. The bore 89 is threaded to receive said traveler 98 as well as a follower 100. The housing 51 surrounding the outer end of the liner 87 is threaded to receive a sealing cap 101 which encloses the liner. The liner may be secured in place by being threaded 15 at its inner end for engagement with the bore 83, and a suitable shoulder may be provided near the inner end of the bore to form a sealing abutment.

Operation of my pumping jack as disclosed in 20 Figs. 1 through 8 is as follows:

The control valve as shown in Fig. 4 and the reciprocator as shown in Fig. 1 are at rest ready to start an up or working stroke. Upon operation of the pump 5, liquid under pressure is introduced through the intake port 60 and passes 25 therefrom to the jack cylinder port 63 into the cylinder base 13 to lift the piston 22. The spring 77 holds the spool valve 74 during such flow of liquid for the reason that the pressure areas at 30 the adjacent sides of the sealing flanges 75 and 76 are equal, and the pressures against their outer sides are likewise equal because the choke valve channel 57 communicates with the exhaust port channel 54 and the head of plunger 81 is 35 exposed through passages 84 and 85 to the exhaust port pressure.

Should the pressure in the jack cylinder port 63, jack cylinder line 3, and cylinder base 13 exceed a predetermined pressure determined by 40 the tension of spring 99, the valve 96 will open and be forced until the valve head engages seat 91. This does two things. First, communication is established from jack cylinder port 63 through 45 passages 86, 93, and 84 to the head of the plunger 81. The tension of spring 77 is such that this pressure overcomes the force thereof and urges the spool valve 74 from the position shown in Fig. 4 to that shown in Fig. 5. As soon as communication is established between jack cylinder 50 port 63 and choke valve channel 57, the pressure in said choke valve channel exerted against the spool valve is sufficient to maintain the valve in the position shown in Fig. 5 during the down stroke. This is due to the fact that the choke 55 valve port 65 is so restricted by the choke valve 68 that a pressure differential exists between the choke valve channel 57 and the exhaust port channel 54 sufficient to overbalance the spring 77.

It should be borne in mind that the piston 22 60 is urged downwardly by the entire weight of the sucker rod string which may amount to several hundred pounds. The pilot valve 94 remains open; that is, in the position shown in Fig. 5, only momentarily for as soon as the spool valve 65 has moved to the position shown in Fig. 5, the pressures in passages 85 and 86 become equalized.

This condition prevails until the dashpot plunger 31 enters the cavity 19 and check valve 35 closes. The weight of the sucker rods now becomes supported by the fluid in the dashpot. The speed of the piston 22 is lowered so that the volume of liquid passing through the jack cylinder port 63 drops until the opening for which the choke valve port is set can no longer maintain a 75

pressure differential between choke valve channel 57 and exhaust channel 54. When this differential drops to the point where it no longer overbalances spring 77, the spool valve is urged to its original position reestablishing communication between the pump 5 and reciprocator.

While liquid is discharging from the pump 5 into the exhaust port 58 during the return stroke of the reciprocator, it should be noted that the capacity of the exhaust port channel 54 and exhaust port itself is sufficiently large to prevent any building up of pressure in opposition to that existing in the choke valve channel 57.

Normally, the pressure rise in the jack cylinder 15 sufficient to reverse the control valve occurs when movement of the piston 22 is restrained by the spring 43. However, should the well pump bind or tend to "sand up", or from any other cause materially increase the load on the polish rod 9, 20 the pressure may rise sufficiently to reverse the valve before the reciprocator completes its working stroke. This operates as a safety feature in at least two ways. First, it is impossible to apply more than a predetermined load on the sucker 25 rods, so that they cannot be pulled in two; and second, if the trouble is due to sanding up of the well pump, reversal in movement of the well pump when it begins to bind tends to work the sand (which may be only a small amount) through the 30 pump, whereupon, as soon as the pump is free of such obstruction, the jack automatically resumes its full working stroke.

It is intended with devices of this kind that they should operate for long periods of time without attention. However, there are times when it is desirable to exert more than the normal tension on the sucker rods, and at such times an operator is in attendance. For example, after the pump has been idle for a period of time, sand 40 or the like in suspension in the oil may be settled around the well pump so that additional force is required to break it loose. This condition is temporary, and in order to permit this function, a modified pilot valve as shown in Fig. 9 may be 45 substituted for the pilot valve described hereinbefore.

In this construction, the housing 51 is substantially the same except that bore 83 may be larger in diameter to accommodate the additional 50 parts required. Fitted in this bore is a liner 111. Similar to the liner 83, the liner 111 is provided with channels 112 which register with passages 84 and 85, and which are provided with ports 113 which communicate with the bore 114 of the liner. Opposite the ports communicating with the passage 85, the bore 114 is constricted as indicated by 115, and inwardly of this constriction forms a check valve chamber 116. The inner end of the liner is threaded to receive a valve plug 117 having a bore 118 therein and a valve seat facing the chamber 116 which is adapted to be engaged by a ball valve 119. The constriction 115 is also provided with a valve seat facing the valve 60 chamber 116 so that the ball valve may engage 65 either valve seat.

The bore 114 is enlarged outwardly from the constriction 115, and mounted therein is the head 120 of a valve tappet from which extends a stem 121 fitting the constriction 115 but fluted to insure 70 free communication between the ports 113 therein and the valve chamber 116. The extended end of the stem 121 is adapted to bear against the ball valve 119.

A spring 122 bears against the head 120 of the tappet; being urged thereagainst by a traveler

123 threadedly engaging the outer portion of the bore 114, and adapted to be locked by a follower 124. The spring 122 regulates the tension on the ball valve and, therefore, the pressure required in passage 86 to open the same. As in the first described structure, the ball valve so fits the valve chamber that upon once being opened, is urged outwardly against the seat of the constriction 115 to seal communication between the passages 84 and 85.

The outer end of the liner is covered by a cap 125 having a threaded boss in its outer end which receives an adjusting screw 126. The adjusting screw 126 is secured in a sleeve 127 which slidably but non-rotatably receives a pin 128 having a head 129 in proximity to the head 120 of the valve tappet. A spring 130 is interposed between the head 129 and the sleeve 127. At the outer end of the sleeve 127, there is provided a sealing washer 131 adapted to seat when the adjusting screw 126 is screwed outwardly as shown in Fig. 9.

Normally, the adjusting screw occupies the outer position shown in Fig. 9 in which position the head 129 clears the head 120 so that the only tension against the check valve is that of spring 122. If, however, it is desired to increase this tension, set screw 126 is turned inwardly until the head 129 bears against head 120 so that both springs 130 and 122 function to hold the check valve 119 seated. The tension of the two springs are so determined that the pressure within the jack cylinder cannot rise to dangerous limits, so that should the operator fail to back off the adjusting screw 126, no damage will occur. As soon as the temporary condition requiring the extra pressure in the jack cylinder has been alleviated, the adjusting screw 126 is returned to its normal position. It should be noted that operation of the adjusting screw in no manner interferes with the adjustment of spring 122.

In both of the pilot valves illustrated, it should be borne in mind that a slight clearance is provided around the check valve, so that should the seat between the check valve and valve plug 92 or 117 leak slightly, no pressure is built up in the 45 passage 84 but is bled out passage 85.

Reference is now directed to Figs. 10, 11, and 12 in which is illustrated a modified form of my pumping jack. In this construction, the control valve is incorporated integrally with the reciprocator. This is accomplished by adding an integral collar 141 to the side of housing 51A intersected by the jack cylinder port 63, so that said port now discharges directly into the collar 141 (housing 51A being identical to the housing 51 except for the changes herein noted). The cylinder base 13 in this arrangement screws into the bottom of the collar 141, while the cylinder 20 screws into the top thereof. In place of socket 82, passages 84, 85, and 86, as well as the bore 83, there is substituted in the housing 51A a constricted bore 142 continuing coaxially with the main bore having the liner 52 therein.

The bore 142 is provided with a sleeve 143 enlarged at its upper end and threaded to receive a bellows shell 144. The shell 144 is cylindrical and supports by its upper end a depending bellows 145 preferably of the "sylphon" type. Attached to the free lower end of the bellows 145 is a bar 146. The bar 146 is adapted to engage the spool valve 74 which, in this construction, is without the plunger 81.

The sleeve 143 is provided near its inner end with an annular channel 147 which communicates with the bore of the sleeve through open-

ings 148. At this point, the bore 142 of the housing 51A is intersected by a laterally directed passage 149 which intersects the choke valve discharge passage 66, so that the interior of the sleeve 143 and shell 144 is at all times subjected to the nominal pressure existing in the exhaust port 58. The bar 146 and sleeve 143, of course, fit as snugly as possible so that leakage through the passage 149 is nominal.

Substituted for the cylinder head 24 is a modified cylinder head 150, into the lower end of which is screwed the cylinder 20. The cylinder head 150 is in most respects similar to the head 24 except that above the cylinder 20 there is mounted a ring 151 held in place by set screws 152 extending through the side walls of the cylinder head. Depending from the ring 151 is an annular bellows 153 having an outer corrugated wall 154 and an inner corrugated wall 155 both sealed to the ring 151 and connected together at their lower extremities by an annulus 156. The annulus 156 is adapted to be engaged by a buffer spring 157 carried by the piston 22 in the manner of the spring 43; said buffer spring 157, however, being lighter in construction.

The ring 151 is provided with an annular channel 158 therein which is intersected by a laterally extending pipe 159. The pipe 159 is adapted to extend outwardly through a boss 160 provided in the head 150, which boss is equipped with a packing gland 161. The pipe 159 is connected by a tube 162 to the bellows 145. The interiors of the bellows 145 and 153 are filled with liquid so that collapsing of bellows 153 expands belows 145.

In addition to the packing gland 161, the boss 160 may be provided with a laterally directed port 163 which may serve as a breather port and to which may be attached suitable air strainer means, not shown. Operation of this form of my pumping jack is as follows:

The spring 71 normally holds the valve 74 in its upper position; in which case, introduction of pressure tends to raise the piston 22 and continues to raise the piston until the spring 157 engages the bellows 153 forcing the liquid therein outwardly through pipe 159 and tube 162 so as to extend the bellows 145 and urge the bar 146 downwardly against the spool valve 74. As soon as the spool valve has been urged to its lower position, the pressure under the piston 22 is available, as in the first described structure, to maintain the spool valve in its lower position.

Attention is now directed to Figs. 13, 14, and 15. In this construction also, the control valve is in most respects identical to that of the first described structure and is designated 51B. The valve housing 51B is joined to a collar 141 similar to the valve 51A but preferably with the exhaust port 58 directed upwardly. The exhaust port 58 is connected through a T 171 to a return line 172 and a riser pipe 173. The riser pipe 173 communicates with a cylinder head 174 so that liquid may be introduced on top of the piston 22. The piston 22 is provided with an upwardly extending dashpot cylinder 175 which is adapted to receive a dashpot plunger 176 depending from the head 174 and loosely surrounding the sleeve 23.

In the present arrangement of the control valve, the plunger 81 of the spool valve and its socket 82 are retained, but in place of the pilot valve structure there is substituted a lateral port 177 which is connected by a tube 178 to a port 179 in the cylinder head 174, which port communicates with the annular space between the dash-

pot plunger 176 and sleeve 23. Operation of this form of my pumping jack is as follows:

The cylinder 20 both above and below the piston 22 is filled with liquid. During the upstroke, the liquid above the piston discharges out the riser 173 and into the line 172. Inasmuch as this is the only fluid flowing in the return line, there is practically no back pressure on the piston. When, however, the plunger 176 receives the dashpot cylinder 175, pressure in the line 178 is raised, building the pressure up in the socket 82 sufficiently to overpower the spring 71 and permit the down stroke of the piston 22. During such down stroke, both the fluid from the pressure source and that discharging from under the piston is delivered to the exhaust port 58. Part of this flows into the top of the cylinder 20 while the remainder returns to the storage tank. Although air may get into the system, liquid amply sufficient to fill the dashpot cylinder 175 is discharged from the riser 173 above the piston 22, thereby insuring proper action of this dashpot.

It is preferred to operate my pumping jack in such a manner as to have a comparatively long and slow up stroke and a comparatively rapid down stroke, as shown in Fig. 16. By adjusting the choke valve 68, it is possible to vary the length of the down stroke, as indicated by the dotted lines in Fig. 16. By adjusting the tension of spring 71, the dashpot action at the lower end of the stroke may be readily varied. For example, the less tension exerted by spring 71, the lower must be the pressure in line 3 in order to permit upward movement of the spool valve. This means that the dashpot plunger 31 must enter deeper into the dashpot 19 and offer greater retarding effect to movement of the piston. On the other hand, the greater the tension of spring 71, the less pressure drop required in line 3, thereby requiring a lesser dashpot action.

With reference to the first described structure, there is no pressure surge at the beginning of the up stroke, and this is due to the fact that the entire effective area of the piston 22 is available during the initial up stroke by reason of the check valve arrangement incorporated in the dashpot plunger 31. Further, even in relatively shallow wells there are several inches of stretch in the sucker rods; consequently, the piston moves an appreciable distance before the entire weight of the sucker rods and well liquid is carried thereby. Therefore, unless the well pump should bind from deleterious matter, no pressure surge occurs until the piston reaches the up end of its stroke.

By reason of the fact that the polish rod 9 extends entirely through the reciprocator, it is readily adjustable up or down without removing the reciprocator. If, however, it is desired to move this apparatus, only the polish rod clamp 28, the line 3, and the union 11 need be disconnected. Upon this being done, the apparatus may be lifted vertically from the polish rod. Also, to adjust the packing gland 15, it is merely necessary to loosen the union 11 and locknut 16, then rotate the follower 12.

Though I have shown and described particular embodiments of my invention, I do not wish to be limited thereto, but desire to include in the scope of my invention the constructions, combinations, and arrangements embraced in the appended claims.

I claim:

1. In a hydraulic pumping jack: a hydraulic reciprocator having a return stroke under urge of an unbalanced load, and a working stroke in

- opposition thereto; a fluid supply means; a valve having a primary position connecting said fluid supply means with said reciprocator for ingress of fluid thereto, and a secondary position for permitting discharge of fluid from said reciprocator; a device operatively associated with said reciprocator for shifting said valve from its primary to its secondary position; means operatively associated with said valve in its secondary position for 5 maintaining a back pressure in said reciprocator during its return stroke; and an instrumentality responsive to a back pressure drop below a predetermined value for urging said valve to its primary position.
15. 2. In a hydraulic pumping jack: a hydraulic reciprocator having a return stroke under urge of an unbalanced load, and a working stroke in opposition thereto; a fluid supply means; a valve having a primary position connecting said fluid supply means with said reciprocator for ingress of fluid thereto, and a secondary position for permitting discharge of fluid from said reciprocator; a pressure responsive device operatively associated with said reciprocator for shifting said valve from 10 its primary to its secondary position; a discharge regulator for said reciprocator operatively associated with said valve in its secondary position to determine the duration of return stroke, said regulator tending to maintain a back pressure in said regulator and against said valve to hold the same in its secondary position; and an instrumentality responsive to a back pressure drop below a predetermined value for urging said valve to its primary position.
25. 3. In a hydraulic pumping jack: a hydraulic reciprocator having a return stroke under urge of an unbalanced load, and a working stroke in opposition thereto; a fluid supply means; a valve having a primary position connecting said fluid supply means with said reciprocator for ingress of fluid thereto, and a secondary position for permitting discharge of fluid from said reciprocator; a device responsive to pressures in said reciprocator above a predetermined value for shifting said valve from its primary to its secondary position; and an instrumentality responsive to a pressure drop in said reciprocator below a predetermined value for shifting said valve from its secondary to its primary position.
40. 4. In a hydraulic pumping jack: a hydraulic reciprocator having a return stroke under urge of an unbalanced load, and a working stroke in opposition thereto; a fluid supply means; a valve having a primary position connecting said fluid supply means with said reciprocator for ingress of fluid thereto, and a secondary position for permitting discharge of fluid from said reciprocator; a device responsive to pressures in said reciprocator above a predetermined value for shifting said valve from its primary to its secondary position; and an instrumentality responsive to a pressure drop in said reciprocator below a predetermined value for shifting said valve from its secondary to its primary position.
45. 5. The combination with a well pump and a sucker rod string extending to the well mouth, of a hydraulic pumping jack comprising: a reciprocator including a cylinder adapted to be mounted over a well mouth, a piston therein, and a polish rod attached to said sucker rod string and adjustably connectible to said piston, said piston having a return stroke under urge of said sucker rod string, and a working stroke in opposition thereto; a fluid supply means; a valve having a primary position for connecting said supply means with said chamber and a secondary position permitting discharge of fluid from said chamber; a device responsive to pressures in said chamber above a predetermined value for shifting said valve from its primary to its secondary position; and an instrumentality responsive to a pressure drop in said chamber below a predetermined value for shifting said valve to its secondary to its primary position.
50. 6. The combination with a well pump and a sucker rod string extending to the well mouth, of a hydraulic pumping jack comprising: a reciprocator including a cylinder adapted to be mounted over a well mouth, a piston therein, and a polish rod attached to said sucker rod string and adjustably connectible to said piston, said piston having a return stroke under urge of said sucker rod string, and a working stroke in opposition thereto; a fluid supply means; a valve having a primary position for connecting said supply means with said chamber and a secondary position permitting discharge of fluid from said chamber; a device responsive to pressures in said chamber above a predetermined value for shifting said valve from its primary to its secondary position; and an instrumentality responsive to a pressure drop in said chamber below a predetermined value for shifting said valve from its secondary to its primary position.
55. 7. The combination with a well pump and a sucker rod string extending to the well mouth, of a hydraulic pumping jack comprising: a reciprocator including a cylinder adapted to be mounted over a well mouth, a piston therein, and a polish rod attached to said sucker rod string and adjustably connectible to said piston, said piston having a return stroke under urge of said sucker rod string, and a working stroke in opposition thereto; a fluid supply means; a valve having a primary position for connecting said supply means with said chamber and a secondary position permitting discharge of fluid from said chamber; a pressure responsive device potentially operative during the working stroke of said piston to shift said control valve from its primary to its secondary position thereby to reverse movement of said piston should the sucker rod load exceed a predetermined value; and an instrumentality potentially responsive during the entire return stroke of said piston to shift said valve from its secondary to its primary position upon drop of pressure in said chamber below a predetermined value, thereby to cause a working stroke of said piston.
60. 8. In a hydraulic pumping jack: a hydraulic reciprocator having a fluid discharging return stroke under urge of an unbalanced load, and a fluid intaking working stroke in opposition thereto; a control valve having a primary position connecting said reciprocator with a fluid supply, and a secondary position for permitting discharge of fluid from said reciprocator; yieldable means urging said valve from its secondary to its primary position; a device operatively associated with said reciprocator for shifting said control

valve in opposition to said yieldable means to terminate the working stroke of said reciprocator; a regulator for metering fluid discharge from said reciprocator during its return stroke, said reciprocator tending to maintain a back pressure in said reciprocator applicable on said valve for holding said valve in its secondary position; and a cushion means operative at the end of the return stroke of said reciprocator to diminish discharge of fluid therefrom and render said regulator ineffective whereby said yieldable means returns said valve to its primary position.

9. In a hydraulic pumping jack: a hydraulic reciprocator having a fluid discharging return stroke under urge of an unbalanced load, and a fluid intaking working stroke in opposition thereto, said reciprocator including a pressure augmenting means operative at the end of its working stroke in conjunction with said load to create a peak pressure in said reciprocator, and a cushion means operative at the end of the return stroke of said reciprocator to create a pressure drop therein; a fluid supply; a discharge line; a back pressure regulator in said discharge line; a control valve having a primary position connecting said fluid supply with said regulator, and a secondary position connecting said reciprocator through said regulator with said discharge line; a device responsive to said pressure peak for shifting said valve to its secondary position; and an instrumentality responsive to said pressure drop for shifting said valve to its primary position.

10. In a hydraulic jack: a hydraulic reciprocator having a common fluid supply and discharge line, and incorporating means tending to create a pressure peak in said line when said reciprocator reaches one end of its stroke, and a means tending to create a pressure drop in said line as said reciprocator reaches the other end of its stroke; a fluid supply; a discharge line; a back pressure regulator in said discharge line; a control valve having a primary position connecting said fluid supply with said regulator, and a secondary position connecting said reciprocator through said regulator with said discharge line; a device responsive to said pressure peak for shifting said valve to its secondary position; and an instrumentality responsive to said pressure drop for shifting said valve to its primary position.

50 11. In a hydraulic jack: a hydraulic reciprocator having a common fluid supply and discharge line, and incorporating means tending to create a pressure peak in said line when said reciprocator reaches one end of its stroke, and means tending to create a pressure drop in said line as said reciprocator reaches the other end of its stroke; a fluid reservoir; a pump having an intake from said reservoir; and a control valve structure interposed between said pump and reciprocator and having a discharge port to said reservoir, said valve structure including a main valve having a primary position connecting said pump with said reciprocator line and a second position connecting both said reciprocator line and pump with said discharge port, yieldable means urging said main valve from its secondary to its primary position, a pilot valve responsive to a pressure peak in said reciprocator line for urging said main valve to its secondary position in opposition to said yieldable means, a meter valve interposed between said port and main valve tending to maintain a back pressure in said reciprocator line applicable to hold said main valve in its secondary position, and means for

rendering said meter valve ineffective to permit operation of said yieldable means.

12. In a hydraulic pumping jack: a hydraulic reciprocator having a return stroke under urge of an unbalanced load, and a working stroke in opposition thereto; a fluid supply means; a valve having a primary position connecting said fluid supply means with said reciprocator for ingress of fluid thereto, and a secondary position for permitting discharge of fluid from said reciprocator; a pressure responsive device potentially operative during the entire working stroke of said reciprocator to shift said control valve from its primary to its secondary position and reverse movement of said reciprocator should the pressure therein exceed a predetermined value, whereby said reciprocator automatically terminates its working stroke; a main regulating element for said device to determine the normal pressure at which said device responds; and an auxiliary regulating element for said device determining an augmented pressure at which said device responds.

13. The combination with a fluid motor, a pressure fluid supply means, and a reservoir, of a control valve comprising: a main valve having a primary position connecting said supply means and motor, and a secondary position connecting both said supply means and motor with said reservoir; yieldable means constantly urging said main valve to its primary position; a pilot valve responsive to pressures in said motor above a predetermined value for urging said main valve to its secondary position; a meter valve interposed between said main valve and reservoir tending to maintain a back pressure in said motor operable to retain said main valve in its secondary position, said yieldable means adapted upon drop in said back pressure below a predetermined value to return said main valve to its primary position.

14. A control valve comprising: a valve body having a pressure fluid intake port, a surge port, and an exhaust port; a main valve incorporated in said valve body and having a primary position connecting said intake port with said surge port, and a secondary position connecting both said surge and intake ports with said discharge port; a pilot valve responsive to pressure in said surge port above a predetermined value to admit fluid against said main valve urging the same to its secondary position; a meter valve interposed between said main valve and discharge port tending to maintain a back pressure in said surge port during flow therefrom to said discharge port, said main valve being held by said back pressure in its secondary position; and yieldable means constantly urging said main valve to its primary position and operative upon drop of said back pressure below a predetermined value.

15. The combination with a fluid supply means; a reservoir; a hydraulic reciprocator having a return stroke under urge of an unbalanced load and a working stroke in opposition thereto; of a control arrangement therefor comprising: a valve having a primary position connecting said reciprocator with said supply means, and a secondary position connecting said reciprocator with said reservoir; means continuously urging said valve into its primary position; a device periodically operable in opposition to said means for urging said valve into its secondary position; and a back pressure regulator for controlling discharge from said reciprocator, said valve including a pressure area exposed to said back pressure when

- said valve is in its secondary position, thereby maintaining said valve in such position in opposition to said means, whereby upon falling off of the back pressure, said valve tends to return 5 to its primary position.
16. In a hydraulic pumping jack: a hydraulic reciprocator having a return stroke under urge of an unbalanced load and a working stroke in opposition thereto; a valve structure for controlling ingress and egress of fluid to and from said reciprocator, said valve comprising a multiple-ported valve body defining fluid paths communicating with said reciprocator; a valve element in said valve body moveable between a primary and a secondary position to control said fluid paths; means continuously urging said valve element into its primary position; a device periodically operable to urge said valve element into its secondary position; and a regulator for one 10 of the fluid paths established when the valve element is in its secondary position tending to maintain a back pressure therein while the fluid velocity therethrough exceeds a predetermined value, said valve element incorporating a pressure area responsive to said back pressure in opposition to said means, whereby when the velocity falls below said predetermined value, said means returns the valve element to its primary position.
17. A valve structure comprising: a multiple-ported valve body; a valve element therein moveable between a primary and secondary position to control fluid paths through said valve body; means continuously urging said valve element into its primary position; a device periodically operable to urge said valve element into its secondary position; a regulator for one of the fluid paths established when the valve element is in its secondary position, said regulator tending to maintain a back pressure therein while the fluid velocity therethrough exceeds a predetermined value.
18. A control valve comprising: a valve body having a pressure fluid intake port, a surge port and an exhaust port; a main valve incorporated in said valve body and having a primary position connecting said intake port with said surge port, and a secondary position connecting both said surge and intake ports with said discharge port; means continuously urging said valve element into its primary position; a device periodically operable to urge said valve element into its secondary position; and a regulator for the fluid path from said surge port to said exhaust port tending to maintain a back pressure at said surge port when the velocity therethrough exceeds a predetermined value, said valve element incorporating a pressure area responsive to said back pressure in opposition to said means, whereby when the fluid velocity through said surge port falls below said predetermined value, said means returns the valve element to its primary position.
19. In a hydraulic pumping jack: a reciprocator including a piston and cylinder means defining a working chamber and an idler chamber, said piston having a return stroke under urge of an unbalanced load and a working stroke in opposition thereto; a pressure liquid supply means; a reservoir; a control valve in communication with both of said working and idler chambers, said supply means, and said reservoir, the control valve having a primary position connecting said supply means with said reservoir and a secondary position connecting both of said chambers and said supply means with said reservoir whereby said idler chamber tends to maintain a charge of liquid therein; means tending to cause a pressure rise in said idler chamber when the piston approaches the end of its working stroke; means for transmitting such pressure to said control valve to shift the same from its primary to its secondary position; and an instrumentality operable at the end of the return stroke of said piston to return said control valve to its primary position.
20. In a hydraulic pumping jack: a reciprocator including a piston and cylinder means, the piston having a return stroke under urge of an unbalanced load and a working stroke in opposition thereto; a pressure fluid supply means; a control valve having a primary position connecting said supply means with said reciprocator to urge the piston through a working stroke, and a secondary position permitting discharge of fluid from said reciprocator during the return stroke of said piston; an auxiliary pressure fluid system including a pressure-exerting element operatively associated with said piston at the end of its working stroke, a pressure transmitting line, and a pressure responsive device associated with said control valve adapted when actuated to shift control valve from its primary to its secondary position; and an instrumentality operable at the end of the return stroke of said piston to return said control to its primary position.

LLOYD SPENCER.
